UNITED STATES PATENT OFFICE.

PHILIP T. DODGE, OF WASHINGTON, DISTRICT OF COLUMBIA, ASSIGNEE TO
MERGENTHALER LINOTYPE COMPANY, A CORPORATION OF NEW YORK.

LINE-CASTING MACHINE.

1,129,078.

Specification of Letters Patent. Patented Feb. 23, 1915.

Application filed December 23, 1911. Serial No. 667,432.

To all whom it may concern:

Be it known that I, PHILIP T. DODGE, a citizen of the United States, and a resident of Washington, District of Columbia, have invented a new and useful Improvement in Line-Casting Machines, of which the following is a specification.

My invention has reference to line casting machines of the Mergenthaler system, in which circulating matrices representing individual characters, stored in a magazine, are delivered by means of finger keys, assembled temporarily in line, with suitable spacing devices, and the line presented temporarily to a mold to form type characters on the edge of a slug cast therein; after which the line of matrices is elevated to a distributing mechanism, by which the individual matrices are returned to the appropriate channels in the magazine.

The invention relates more particularly to those machines in which superposed magazines, each carrying a font or series of matrices, are movable vertically at the will of the attendant in order that one or another of the magazines may be brought into operative relation to the distributing mechanism above and the assembling mechanism below, as first shown in Letters Patent of the United States No. 548,432 issued to me on the 22d day of October 1895.

In the machine described in this patent the escapements are located in a stationary throat forming a continuation of the magazine in operative position, and the organization is such that two matrices from each channel are normally held in this throat, outside of the magazine. Before it is possible to effect the adjustment of the magazines it is necessary to push these matrices backward into the magazine—a very difficult operation—or to pass them through the machine and through the distributing mechanism, in order to restore them to the magazine.

The main objects of the present invention are as follows:

The first object is to avoid the retention of matrices beyond the lower end of the magazine, so that the adjustments of the magazines may be made at any instant, and without loss of time.

To this end the invention consists in combining with movable magazines a series of external escapements so constructed and ar-

ranged that each matrix released from a magazine is permitted to pass directly to the line in course of composition.

The second object of the invention is to provide for the automatic locking of the matrices within those magazines which are not for the time being in use, and for automatic unlocking of the matrices in each magazine as it is brought to the operative position.

To this end it consists in combining with the magazine means for locking the matrices therein and means for automatically actuating said locking devices.

With the exception of the parts herein-after specifically described the machine may be of the construction represented in the above named patent or of the construction shown in application for Letters Patent filed by J. R. Rogers on May 1st, 1911, Serial No. 624,426.

In the drawings: Figure 1 is a side elevation of the upper part of the machine with my improvements incorporated therein. Fig. 2 is a vertical longitudinal section through the lower end of the magazines and adjacent parts, the escapements being in their normal positions, or positions of rest. Fig. 3 is a side elevation showing the details of the matrix locking mechanism. Fig. 4 is a vertical cross section through one side of a magazine, showing the matrix locking device. Fig. 5 is a section on the line 5—5, Fig. 3, looking in the direction indicated by the arrow. Fig. 6 is a vertical section on the line 6—6, Fig. 7. Fig. 7 is a side view, looking from the right of the machine, of portions of the magazines and escapement mechanism in vertical section. Fig. 8 is a view of a matrix. Fig. 9 is a vertical sectional view of the forward end of a magazine, showing the escapement in its first or abnormal position, with a matrix released from the magazine but arrested momentarily while the second matrix is being engaged. Fig. 10 shows a matrix of modified form, with one of its ears beveled.

Referring to the drawings, A A represent portions of the mainframe, B the usual Mergenthaler distributing mechanism, secured to the upper part of the frame; C a stationary face plate or throat, having vertical channels to receive the matrices W, delivered from the lower end of the magazine; D the endless belt which receives the matrices from

said channels and delivers them successively to the usual assembling or composing mechanism.

5 E, E', E², etc., are a series of superposed magazines, each consisting of two parallel plates secured to intermediate spacing blocks, and grooved longitudinally in their inner opposing faces, to guide the upper and lower edges of the matrices which are delivered into the upper end of the magazines from the distributor, and delivered, in turn, from the lower end of the magazine into the face plate C.

10 F is a base frame on which the series of magazines are supported; G a column fixed to and supporting the base frame; and H, a sleeve or tube forming part of the main-frame, and serving to guide the column G.

15 I is a screw mounted in the lower end of the sleeve H, for the purpose of raising and lowering the column G and the series of magazines.

20 J is an actuating gear secured to the lower end of the screw and receiving motion from the gear K, which is in turn connected by a jointed shaft L, to a hand crank M, at the front of the machine, so that by turning the crank the attendant may raise or lower the magazines, bringing any one of the series 25 into operative relation with the distributing and assembling mechanism.

25 N is a locking bar mounted to slide endwise in bearings on the mainframe, and arranged to engage at its ends in grooved plates O, secured to the frame which sustains the magazines, this bar serving to lock the magazine which is for the time being in use solidly and accurately in position, so that its upper and lower ends will be in exact 30 alignment with the coöperating parts.

35 All of the parts so far as described may be identical in construction with those shown in the Rogers application above referred to, or of any other suitable construction, my 40 invention having no reference thereto.

45 In carrying my invention into effect I mount on the mainframe a stationary throat P, having internal grooves or channels forming continuations of those in the magazine 50 which is for the moment in operative position. This throat is designed to receive and successively guide the outgoing matrices W, and direct them downward to the face plate.

55 For the purpose of effecting the delivery of the matrices one at a time from the magazine, I provide on the lower side of the stationary throat P, a series of escapements Q, one for each channel of the magazine. 60 These escapements may be made of various forms, but in the form shown they consist each of a lever mounted at or near the middle on a horizontal pivot e, and having at opposite ends two lips or studs, extending upward 65 through openings in the underside of the

throat, the form and arrangement being such that the rocking movement of the escapement on its pivot will cause the two lips to be projected upward alternately into the path of the matrices.

70 The lip at the upper end of the escapement stands normally in the position shown in full lines in Figs. 2 and 6, so that it engages against the outer or lower end of the foremost matrix, holding the same in the 75 magazine. When the position of the escapement is reversed the upper lip is retracted and the matrix permitted to escape from one magazine, while at the same time the lower lip is elevated to such a position that it 80 engages the lower end of the outgoing matrix, as shown in Fig. 9, momentarily arresting its advance. The upper end of the matrix thus arrested bears against and holds back within the magazine, the second matrix, which has advanced to take its place. The escapement is next returned to its original position; whereupon its upper end engages and holds the second matrix within the magazine, at the same time releasing the 85 first one, and permitting it to pass downward to the line in course of composition.

90 The escapement is acted upon by a spring g', which normally holds its upper end in the elevated position shown in Figs. 2 and 7.

95 In order to permit the engagement of the escapement with the front of the second matrix, within the magazine, while it is being held back by the first or detained matrix, I prefer to cut away the upper end of the 100 matrices on the under sides as shown in Figs. 2 and 9 and at w in Fig. 8. This recess may be of angular form, as shown in Fig. 8, or the ear of the matrix may be beveled, as in Fig. 10, the only requirement being that 105 space shall be afforded between the upper end of one matrix and the lower end of the next for the admission of the escapement.

110 The action of the escapement may be effected by any suitable means, preferably by a vertical reed R guided in the main frame, and lifted at intervals by a cam mechanism such as shown, controlled in its action by a finger key, S. The cam mechanism shown is identical with that commonly used in 115 Mergenthaler machines of the present day and described in detail in Letters Patent of the United States No. 530,931 issued to me on December 18th, 1894. As this mechanism is familiar to all skilled in the art, 120 it is deemed unnecessary to describe its details herein.

125 Whenever a finger key is operated the reed R is lifted mechanically, and the escapement moved against the action of the spring, and then released, that the escapement may be restored to its original position, the effect being the release of a matrix whenever a key is depressed.

130 It will be observed that the final release

of the matrix is effected by the second movement of the escapement, that no matrix is permanently retained outside of the magazine, and that in this important respect the structure shown differs from that shown in my Patent 548,432.

It will be observed that in the mechanism herein shown all of the matrices are retained normally within the magazines, which are at all times free to rise and fall.

Inasmuch as the magazines are without escapements it is necessary to provide means for locking the matrices therein—except in the one magazine which is for the time being in action. For this purpose I mount transversely in the top of each magazine a rock shaft T , flattened on one side, the proportions and arrangement being such that when turned to one position the flattened face of the shaft will overlie the path of the matrices, and permit them to pass freely, as shown in the magazine next to the top one in Fig. 2; while on the other hand, if the shaft is given a quarter rotation, so that its vertical face is perpendicular to the path of the matrices, it will engage the upper ears of the lowermost matrices and lock them within the magazine, at the same time forcing the matrices slightly upward within the magazine, so that their lower extremities will not protrude, or contact with any external surfaces. These shafts are not individually claimed, as they form the subject matter of Letters Patent of the United

States No. 776,779, granted to me December 6th, 1904. For the purpose of turning these shafts automatically, I provide each of them at the outer end with a crank arm t , preferably with an anti-friction roller at the extremity, and I mount on the main-frame a vertical flange or guide, U , against which these crank arms travel as the magazines are raised and lowered. At a point just above the operative magazine this guide

U is provided with a hinged portion u , which may be turned backward or downward, as shown in dotted lines, to afford an opening through which the crank arm on the operative magazine will swing, as indicated in dotted lines in Fig. 3, thus turning the shaft to a position to unlock the matrices. When this hinged portion is restored to its original position it turns the crank, and causes the rock shaft to lock the

matrices in the operative magazine before that magazine is moved from the operative position. This movement may be effected by any suitable means, but I prefer, as shown in Fig. 1, to provide the member u

60 with a crank arm u^1 , connected by a link u^2 , to a lever u^3 , which actuates the locking bar N as heretofore. This lever u^3 is connected by a link u^4 , an angular lever u^5 , and a rod u^6 , with a plate u^7 , connected to

65 the hand crank, so that when this crank is

pushed inward as in the Rogers application, to unlock the magazines, it will at the same time cause the member u to turn the rock shaft and lock the matrices in that magazine which is in use. On the other hand, whenever a magazine is raised or lowered to the operative level, the crank on its rock shaft will be brought opposite the member u , and when the bar N is moved to lock the magazines the member u will permit the rock 70 shaft to unlock the matrices, so that they may be discharged by the escapements.

The weight of the matrix columns tends to turn the rock shafts from the locked to the unlocked position, but I prefer to apply 80 to each shaft a coiled spring v , tending to turn it to the unlocked position.

From the foregoing it will be understood that whenever the magazines are to be raised or lowered, the matrices will be 85 locked within the magazines, in advance of their movement, and that whenever a magazine reaches the operative position its matrices alone will be unlocked and made subject to the control of the escapements. 90

While I prefer to make use of the rock shafts as the best means for locking the matrices within the magazines, and to operate them by means of crank arms as described, it is to be understood that any 95 equivalent mechanism, carried by the magazines, may be employed; and that the locking mechanism may be actuated by any suitable devices.

It is also to be understood that the escapements may be varied in form, provided that they have a mode of action substantially the same as herein shown, the requirements being that they shall by the first movement release a matrix from the magazine, and by a 105 second or final movement discharge the first matrix and hold the second within the magazine.

It will be understood that two, three or four magazines may be employed: and it is 110 also to be understood that in place of the Mergenthaler distributing mechanism herein shown, any other suitable means may be employed for returning the matrices to the upper end of the operative magazine, these 115 means, which are foreign to my invention, being already known in various forms to persons skilled in the art.

My invention is of course applicable to machines which carry matrices for type, and to machines which carry type dies or type in the magazine—in short to all typographic machines in which circulating type members are employed.

Having described my invention, what I 125 claim is:

1. In a typographic machine, a main-frame and magazines movable therein that any one may be brought to an operative position, in combination with a fixed series 130

of escapements located beyond the delivery ends of the magazines to control the discharge of matrices therefrom, and means independent of the escapements carried by the 5 magazines and controlled by their movement to prevent the escape of matrices from those magazines which are in inoperative positions.

2. In a typographic machine, a main- 10 frame, a fixed throat to receive matrices released from a magazine, and a fixed series of escapements acting in said throat to control the delivery of individual matrices from the magazine, in combination with a 15 series of magazines movable in relation to the throat, that any magazine may be brought into operative relation therewith, and automatic means carried by the magazines and controlled by their movement to 20 lock matrices therein when they are in inoperative positions.

3. In a typographic machine, the combination of magazines movable at will that any one may be brought to the operative 25 position, a fixed channeled throat through which the matrices are discharged from the operative magazine, escapements acting each by its first movement to release a matrix from the magazine into the throat, and by 30 its second movement to discharge said matrix and retain the next one within the magazine, and adjustable means controlled by the movement of the magazines for confining the matrices within the inoperative 35 magazines.

4. In a typographic machine, a number of magazine movable at will that any one may be brought to the operative position, and automatic means controlled by the movement 40 of the magazines for locking the matrices in each magazine when in an inoperative position and releasing them when it is brought to an operative position, said locking means being distinct from the 45 escapement mechanism.

5. In a typographic machine, the combination of a plurality of magazines movable as a whole to bring any selected one into operative position, rocking members carried 50 by said magazines to lock the matrices therein, and stationary means to coöperate with the rocking members during the movement of the magazines to cause the locking of the matrices in the inoperative magazines and 55 the unlocking of the matrices in the operative or selected magazine.

6. In a typographic machine, the combination of a plurality of magazines movable as a whole to bring any selected one into 60 operative position, rock shafts mounted in each of the magazines, operating members on the ends of said shafts, and stationary members to coöperate with said operating members during the movement of the magazines

to effect the locking and unlocking of the 65 matrices in the inoperative and operative magazines respectively.

7. In a typographic machine, the combination of a plurality of magazines movable as a whole to bring any selected one into operative position, rock shafts mounted in the magazines and provided with crank arms, and a stationary plate U provided with a rocking plate u to operate the crank arm of the rock shaft carried by the selected magazine.

8. In combination, the movable magazines with means for locking the matrices therein, the fixed series of escapements beyond the magazines to control the delivery of the 80 matrices from one magazine at a time, means for locking the magazines in their adjusted positions, and connections between the matrix locking and magazine locking devices whereby the locking of the matrices is insured before the movement of the magazines.

9. In a machine of the class described, a series of movable magazines without escapements but with means for locking the matrices therein, the fixed series of escapements 90 to control the delivery of matrices from one magazine at a time, means for raising and lowering the magazines and for locking them in position, and connections between the devices for moving the magazines, the 95 devices for locking the same, and the devices for locking the matrices, whereby the matrices in the inoperative magazines are secured against accidental discharge, and the matrices in the operative magazines placed 100 under the control of the escapements.

10. In a typographic machine comprising matrices each having an open notch in its upper corner, the combination of a magazine to contain the matrices and movable at will from its operative position, and a series of escapements mounted independently of the magazine and beyond its delivery end to control the passage of the matrices therefrom, the upper end of each of the escapements normally engaging the lower end of the lowermost matrix to hold it within the magazine and adapted to enter the notch in the upper corner thereof in its return to normal position.

11. In a typographic machine comprising matrices each having an open notch in its upper corner, the combination of a magazine to contain the matrices and movable at will from its operative position, a series of escapements mounted independently of the magazine and beyond its delivery end to control the passage of the matrices therefrom, the upper end of each of the escapements normally engaging the lower end of the lowermost matrix to hold it within the magazine and adapted to enter the notch in the upper corner thereof in its return to normal position.

tion, and locking devices to retain the matrices within the magazine when moved from its operative position.

12. In a typographical machine comprising matrices each having an open notch in its upper corner, the combination of a plurality of magazines to contain the matrices and movable as a whole to bring any selected one into operative position, an assembling throat to receive the matrices from the operative magazine, and a series of escapements acting in said throat to control the passage of the matrices therethrough, the upper end of each of said escapements normally engaging the lower end of the lower-most matrix to hold it within the operative magazine and adapted to enter the notch in the upper corner thereof in its return to normal position.

13. In a typographic machine, the combination of a magazine for the type or matrices and movable at will from its operative position, and a single series of escapements mounted independently of the magazine beyond its delivery end and acting solely to control the release of the type or matrices therefrom, the said escapements being arranged with their upper ends in position to hold the lowermost type or matrices within the magazine together with locking devices independent of the escapements to retain the type or matrices within the magazine when it is moved from operative position.

14. In a typographic machine, the combination of a fixed assembling throat, a plurality of magazines movable as a whole to bring any selected one into operative rela-

tion thereto, and a single series of escapements located within the throat with their upper ends in position to hold the lowermost 40 matrices within the operative magazine and acting solely to control their release therefrom together with locking devices independent of the escapements to retain the matrices within the inoperative magazines. 45

15. In a typographic machine, the combination of a plurality of magazines movable as a whole to bring any selected one into operative position, a fixed throat through which the matrices pass from the operative 50 magazine, and a single series of escapements acting each by its first movement to release the matrix from the magazine into the throat, and by its second movement to discharge said matrix and retain the next one 55 within the magazine together with locking devices independent of the escapements to retain the matrices within the inoperative magazines.

16. In a typographic machine, a plurality 60 of magazines movable as a whole to bring any selected one into operative position, and each provided with a matrix locking device which is moved automatically to locking and unlocking position as the corresponding 65 magazine is moved out of and into operative position, respectively.

In testimony whereof I hereunto set my hand this 13th day of December, 1911, in the presence of two attesting witnesses.

PHILIP T. DODGE.
